WITNESS.

J. INVENTOR

UNITED STATES PATENT OFFICE.

WALTER H. LIVINGOOD, OF BERKELEY, CALIFORNIA.

PISTON FOR INTERNAL-COMBUSTION ENGINES.

1,404,621.

Specification of Letters Patent. Patented Jan. 24, 1922.

Application filed February 12, 1921. Serial No. 444,465.

To all whom it may concern:

Be it known that I, WALTER H. LIVINGOOD, a citizen of the United States, residing at Berkeley, in the county of Alameda and State of California, have invented new and useful Improvements in Pistons for Internal-Combustion Engines, of which the following is a specification.

This invention relates to internal combustion engines and has more particular reference to the pistons therefor, the primary object being to provide a novel structure of piston by the use of which the wrist pin is effectively prevented from contact with the inner wall of the cylinder whereby scoring and damage thereof is prevented.

Another object of this invention is to provide means whereby effective lubrication of the wrist pin and piston are attained.

A further object of this invention is the provision of a piston more particularly adapted for internal combustion motors which is simple in construction, comprises but few parts, said parts being of a nature whereby in the event of renewal or repair they can be readily disassembled and as easily re-assembled after repair or renewal has been effected.

With the foregoing and other objects in view as will later on be more apparent my invention consists essentially in the novel features of construction, combination and arrangement of parts hereinafter particularly described and more specifically defined by the appended claims.

In the drawings:

Figure 1—is an elevation of a piston embodying my improvements.

Figure 2—is a longitudinal central section of the same.

Figure 3—is an end view looking toward the left hand of the preceding figures; and,

Figure 4—is an end view of an inner element or part later on more particularly referred to.

Referring in detail to the drawings wherein like characters of reference designate the same or corresponding parts in all the views the numeral 10 indicates the upper half of what I prefer to designate the cap portion of the improved piston and 11 the lower half or skirt portion thereof. Formed integral with the upper half or cap portion 10 is a rectangular head 12 which provides a means whereby the parts 10 and 11 may be tightly screwed together by the employment

of a wrench or other appropriate tool. The wrist pin is designated by the numeral 13 and it is to be observed that said wrist pin is of a length over all such that it will not project beyond the outer surface or wall of the piston and thereby cannot scrape or contact with the inner wall of the cylinder in which the piston is operating.

In order to provide adequate means for properly lubricating the wrist pin 13 I form longitudinally thereof a groove or channel 14 for the purpose later on explained. Internally of the cap piece 10 which it will be noted is made hollow I form a screw threaded portion 15 into which is threaded a correspondingly threaded part of the inner extended part 16 of the skirt portion 11, said inner cylindrical part being cut away about its outer peripheral portion to provide an annular oil collecting chamber 17 and said chamber being supplied with oil due to the splash set up by the crank—not shown—when the piston is in motion. The oil splashed up by the crank when in motion is thrown on to the inner wall or surface 18 of the cylindrical part or member 16 and is conducted to the oil chamber 17 through the radial holes or ports 19 and V-shaped angled groove 20 in the crown or top end of said cylindrical part or member 16. The oil thus collecting in the chamber 17 is fed through holes or passages 21 to the wrist pin 13 and the groove 14 as will be clearly understood on an examination of the drawings. It is to be here particularly noted that I preferably make the wrist-pin tubular or provided with a bore 22 axially therethrough in order to reduce the weight of metal therein.

Furthermore it is to be observed that the wrist pin 13 is cut away or shouldered at 23 so that the cap portion 10 can be screwed into position and as readily removed, whilst an effective means is furnished for preventing the rotation or longitudinal displacement of said wrist pin 13. This feature of my invention I deem of great importance as it will be readily understood that the lower half of the ends of the wrist pin 13 can be easily made to conform approximately to the peripheral contour of the skirt 11 and thereby present an unbroken working surface.

The connecting rod 24 is preferably fitted to the wrist pin 13 by means of a bushing 25, and which constitutes the only movable bearing or other element in my improved

piston, and it is to be seen that there are provided opposed bosses 26 in the skirt portion, 11 for housing the wrist pin 13. Grooves 27 are provided in the cap piece 10 for the accommodation of the usual piston rings—not shown.

From the foregoing it will be readily seen that by my invention I provide a simple and effective structure of piston for internal 10 combustion engines, and whilst there has been described the best form thereof at present known to me, it is to be understood the invention is susceptible of various changes in its form, proportions and minor details of 15 construction, and the right is hereby reserved to make such changes as properly fall within the scope of the appended claims.

Having described my invention what I claim as new and desire to procure by Letters Patent is:—

1. A piston for internal combustion engines comprising in combination inter-engageable sections one of which is provided with an annular reduced portion constituting 25 a lubricant reservoir, a wrist-pin having notched ends adapted for engagement by the inter-engageable sections whereby it is maintained rigid, and means for conducting lubricant to the aforesaid reservoir 30 and feeding same to the wrist-pin.

2. A piston for internal combustion engines comprising in combination inter-connectable sections one of which constitutes a cap portion and the other the support 35 therefor and having a hollow extension adapted to fit within said cap portion, an annular reduction in the hollow extension constituting a lubricant reservoir, a wrist-pin having notched ends adapted for engagement 40 by the inter-connectable sections whereby it is maintained rigid, and means for conducting lubricant to the aforesaid reservoir and feeding same to the wrist-pin.

3. A piston for internal combustion engines comprising in combination inter-connectable sections one of which constitutes a cap portion and the other the support 45 therefor and having a hollow extension

adapted to fit within said cap portion, a tubular wrist-pin having notched ends adapted 50 for locking engagement by the inter-connectable sections, radial passages in the body and angular grooves in the inner end of the hollow extension serving as feed openings into the lubricant reservoir and longitudinal 55 passages connecting said lubricant reservoir with the wrist-pin whereby the lubricant is fed thereto.

4. A piston for internal combustion engines comprising in combination inter-connectable sections one of which constitutes a cap portion and the other the support therefor and having a hollow extension adapted to fit within said cap portion, a tubular wrist-pin having a longitudinal groove 60 in the outer wall thereof, radial passages in the body and angular grooves in the inner end of the hollow extension serving as feed openings into the lubricant reservoir, and longitudinal 65 passages connecting said lubricant reservoir with the aforesaid longitudinal groove in the wrist-pin whereby the lubricant is fed thereto.

5. A piston for internal combustion engines comprising in combination inter-connectable sections one of which constitutes a cap portion and the other the support therefor and having a hollow extension adapted to fit within the cap portion, a tubular wrist-pin having a longitudinal groove in the outer 70 wall thereof, radial passages in the body and angular grooves in the inner end of the hollow extension serving as feed openings into the lubricant reservoir, longitudinal 75 passages connecting said lubricant reservoir with the aforesaid longitudinal groove in the wrist-pin whereby the lubricant is fed thereto, and means on the aforesaid cap portion whereby it can be manipulated into 80 inter-connecting engagement with the wrist-pin and supporting section.

In testimony whereof I affix my signature.

WALTER H. X LIVINGOOD.
